UNITED STATES PATENT OFFICE.

DAVID J. HAUSS, OF AURORA, INDIANA.

MUSIC-PLAYER TRACKER MECHANISM.

1,128,976.

Specification of Letters Patent. Patented Feb. 16, 1915.

Application filed March 9, 1911. Serial No. 613,262.

To all whom it may concern:

Be it known that I, DAVID J. HAUSS, a citizen of the United States, residing at Aurora, in the county of Dearborn and State 5 of Indiana, have invented certain new and useful Improvements in Music-Player Tracker Mechanism, of which the following is a specification.

My invention relates to tracker mechanism for music players.

One of its objects is to provide a sectional tracker board and means whereby the respective sections can be adjusted to track with commercial sheets cut to different 15 scales transversely of the sheet.

Another object is to provide improved mechanism to transversely adjust the sections of the tracker board with accuracy.

Another object is to provide an improved 20 sectional tracker board capable of transverse adjustment, and means to render the sections near the ends of the tracker board inoperative when desired.

My invention further consists in certain 25 details of form, combination and arrangement, all of which will be more fully set forth in the description of the accompanying drawings in which:

Figure 1 is a front elevation of a pair of 30 sheet feeding rolls with my improved tracker in extended position. Fig. 2 is a sectional diagram on line $z-z$ of Fig. 1. Fig. 3 is a view similar to Fig. 1 of a portion of a tracker board with the sections adjusted 35 to another position. Fig. 4 is a perspective view of one of the adjusting bars detached. Fig. 5 is a perspective view of one of the tracker board sections detached. Fig. 6 is a perspective view of a portion of a tracker 40 board and illustrating a modification. Fig. 7 is a sectional detail on line $v-v$ of Fig. 6. Fig. 8 is a front elevation of a portion of a tracker-board illustrating another modification. Fig. 9 is a sectional detail on line $x-x$ of Fig. 45 of Fig. 8. Fig. 10 is a view similar to Fig. 4 of a similar member for adjusting the tracker bar sections of Figs. 8 and 9.

My invention is adapted to be applied to 50 tracker mechanism of either electrical or pneumatic type.

The accompanying drawings represent the preferred embodiments of my invention. In Figs. 1 to 5 A represents part of a sup-

porting frame in which are supported sheet delivery roll B and take-up roll C and a 55 tracker board D comprising a series of independent sections each provided with an electrical contact finger. The several contact fingers are adapted to close independent electrical circuits which serve to actuate 60 the keys or equivalent members of a musical instrument by making contact with a contact member E through perforations in the music sheet F.

In different music sheets the perforations 65 are cut to different scales transversely of the sheet, as for instance, some sheets may be cut to a scale of 44 notes six to the inch, others to 65 notes six to the inch, and others 88 notes nine to the inch. In my improved 70 tracker the tracker board is composed of a series of separate or independent sections 2 which are composed preferably of insulating material and are mounted side by side upon rods or guides 3. The central tracker 75 board section 2' is preferably rigidly connected to the rods 3 by screws 4, and the sections 2 at opposite sides of the section 2' are free to move along the guides or rods 3, and are pressed toward each other by means 80 of springs 5 which are partly incased in tubes 6 and bear at their outer ends against the cross bars 7 which serve to lock the rods 3 together at opposite ends. The rods 3, tubes 6 and cross-bars 7 constitute a movable 85 tracker board frame, which carries the sections 2 and their adjusting mechanism. The tubes 6 have bearings in the main frame A and are adapted to slide endwise in said 90 bearings to shift the tracker board transversely of the sheet feed to transpose the music. A rod 8 through suitable mechanical connections serves to shift the tracker board and lock it to adjusted position. The centers $c-c'$ are adapted to receive and support sheet 95 rolls of different length, and the take-up roll is sectional to permit it to be adjusted to receive sheets of different width. The mechanism for adjusting the tracker board transversely; adjusting the sheet rolls; and 100 the transposing members, is preferably the same as fully illustrated and described in my application Serial No. 525,694, filed November 1, 1909.

In order to adjust the several tracker 105 board sections 2 to the desired positions to

aline with the perforations of sheets cut to different scales I provide a series of tapered bars or members 9 which are slotted at 11 to receive the rods 3, and at 12 to receive the cross bars 10 which are rigidly connected to the opposite sides of the frame A. The bars 9 are thus free to slide along the rods 10 and also by reason of the slots 11 and 12 are capable of adjustment endwise. 5 14 represents a cylindrical bar eccentrically pivoted to the opposite sides of frame A and provided with a hand lever 15 by means of which it may be partially rotated, and a dog or pawl 16 engaging a circular 10 notched plate 17 on frame A, by means of which the eccentric 14 may be locked to any adjusted position. The bars 9 are provided with straps 18 which with the end of said bars serve to encircle said eccentric 15 14 so that said eccentric serves to simultaneously adjust said bars 9 endwise to vary the extent to which the tapered portion of said bars is inserted between the tracker board sections 2, thereby serving to 20 variously space said tracker board sections. The springs 5 serve to hold the adjacent faces of the tracker board sections and the bars 9 firmly in contact and to yieldingly provide for the extension and retraction of 25 the tracker board.

The respective tracker board sections 2 are provided with metal tubes 19 into one end of which the upper ends of spring contact fingers 20 are detachably inserted, 30 while the ends of the electrical circuit wires are adapted to be inserted into the opposite ends of tubes 19. Lugs 21 preferably formed integral with the sections 2 serve to support the free ends of the contact fingers 40 in alinement, while rods 22 are inserted through the eyes 23 of one or more of said sections at opposite ends of the tracker board, where they serve to engage the curved portion 24 of the contact fingers so 45 as to retract such contact fingers as are engaged by the rods 22 from operative relation with the sheet and contact member E, thus enabling as many contact fingers as desired at either end to be thrown out of 50 operation, either for the purpose of transposition or upon changing to sheets of greater or less number of notes.

The contact member E is preferably a roller pivotally supported by a frame 30 55 which is pivoted at 31 and adapted to swing the member E into and out of contact with the sheet and to force the sheet into operative relation with the contact fingers. When the member E is out of engagement with the sheet as for rewinding or like purpose, the sheet is out of contact with the fingers 20 and assumes the position indicated in dotted line Fig. 2. The sheet roll supporting and adjusting and driving 60 mechanism, and the means for adjusting the 65

tracker board and members 22 may be substantially as illustrated and described in my application Serial No. 525,694.

In the modification Figs. 6 and 7 the several tracker board sections 35 are provided 70 with ears 36 on one side and ears 37 on the other side. Eccentric rods 38 are pivoted on one axis to ears 36 of one section and on the other axis to ears 37 of the next section. The several eccentrics 38 are provided with 75 crank arms 39 which are connected in pairs by links 40 and adapted to be shifted to rotate the eccentrics 38 to shift the sections 35 to or from each other on the rods 41, 42, by means of eccentric rods 43 operated by 80 a common eccentric 44.

In Figs. 8, 9 and 10 I have illustrated my invention applied to a pneumatic tracker board in which 50 represents a series of independent sections constituting a pneumatic 85 tracker board, said several sections being supported side by side upon rods 51, 52 corresponding to the rods 3 of Fig. 1. Each section is provided with an air duct 53 adapted to be normally closed by a music 90 sheet, said ducts leading by means of flexible tubes 54 to pneumatically actuated mechanism adapted to actuate the keys or equivalent mechanism of a musical instrument. Springs 5, not shown in these figures, serve to press the sections 50 into contact with each other, while tapered bars 55 actuated by an eccentric rod 56 as heretofore described, serve to separate the sections 50 to a greater or less extent as desired. A 100 member 57 corresponding in function to the rods 22 of Fig. 1 serves to cover the air ducts of one or more of the end sections of the tracker board. If desired rods identical with the rods 22 of Fig. 1 may be employed 105 to actuate valves to close the air ducts of the sections 50.

The mechanism herein illustrated and described is capable of considerable modification without departing from the principle 110 of my invention.

Having described my invention, what I claim is:

1. In a tracker board for musical instruments, a plurality of separate sections adjustably supported upon said tracker board frame, a plurality of wedges interposed between said sections, and means to actuate said wedges in unison.

2. A tracker board for musical instruments comprising a plurality of adjustable sections corresponding to the sounding members of the musical instrument, and mechanism interposed between said tracker board sections to adjust said sections uniformly to vary the distance from center to center of said tracker board sections.

3. In a mechanism of the character described, mechanism adapted to feed a music sheet, a tracker comprising a series of ad- 130

justable sections, a plurality of wedges interposed between said tracker board sections, means to yieldingly force said tracker board sections together, and mechanism to 5 actuate said wedges in unison to vary the distance from center to center of said tracker board sections.

4. A tracker board for musical instruments comprising a plurality of adjustable 10 sections, a plurality of wedges interposed between said tracker board sections to vary the distance from center to center of said tracker board sections, and mechanism to shift said tracker board as a whole trans- 15 versely of the sheet feed.

5. A tracker board for musical instruments comprising a tracker board frame, a plurality of tracker board sections adjustable to and from each other on said tracker 20 board frame, springs at opposite ends of said tracker board frame to force said sections together, and mechanism engaging said sections and operable to force said tracker board sections apart against the ac- 25 tion of said springs.

6. In a mechanism of the character de- 30 scribed, a tracker board comprising a tracker board frame adjustable transversely of the sheet feed, a guide carried by said frame, a plurality of tracker board sections each pro- 35 vided with a music key controlling member and adjustably supported by said guide, members carried by said tracker board frame serving to normally force said sec- 40 tions toward each other, and mechanism car- 45 ried by said frame to force said sections apart.

7. In a mechanism of the character de- 40 scribed, a tracker board comprising a tracker board frame, a guide carried by said frame, a plurality of tracker board sections each provided with a music key controlling mem- 45 ber and adjustably supported by said guide, members carried by said tracker board frame adapted to yieldingly hold said sections in a retracted position, and a plurality of tapered members to shift said tracker board sections to an extended position.

8. In a mechanism of the character de- 50 scribed, a tracker board frame, a plurality of tracker board sections mounted upon guides carried by said frame, members car- 55 ried by said respective tracker board sections to control the music keys, mechanism to adjust said sections to and from each other, and adjustable members at opposite ends of the tracker board to engage the key-

controlling members of said sections at op- 60 posite ends of the tracker board to render said key controlling members inoperative.

9. A tracker board for musical instru- 65 ments comprising a tracker board frame, a plurality of tracker board sections each provided with a music key controlling mem- 70 ber and adjustably supported upon said tracker board frame, and means interposed between said tracker board sections to uni- 75 formly vary the distance from center to center of said tracker board sections.

10. A tracker board for musical instru- 70 ments comprising a tracker board frame ad- 75 justable transversely of the sheet feed, a plu- 75 rality of sections constituting a tracker board and adjustably supported to slide upon said tracker board frame, a plurality 80 of music key controlling members carried by said tracker board sections, and mechanism to adjust said sections to uniform degree to and from each other.

11. A tracker board for musical instru- 80 ments comprising a tracker board frame ad- 85 justable transversely of the sheet feed, and a tracker board comprising a plurality of tracker board sections corresponding to the respective keys of the musical instrument 85 supported upon said tracker board frame and each provided with a music key con- 90 trolling member, one of said sections being rigidly supported relative to said frame and the remaining tracker board sections being 90 adjustable to and from said rigidly sup- 95 ported tracker board section.

12. A tracker board for musical instru- 95 ments comprising a tracker board frame ad- 100 justable transversely of the sheet feed, a tracker board composed of a plurality of tracker board sections supported upon said tracker board frame, and each provided with a music key controlling member, one of said sections being rigidly supported rel- 105 ative to said frame and the remaining sec- 105 tions being adjustable to and from said rigidly supported tracker board section, a plu- 110 rality of wedges interposed between said tracker board sections, and means to actuate said wedges to adjust said tracker board sec- 115 tions to and from each other.

In testimony whereof I have affixed my signature in presence of two witnesses.

DAVID J. HAUSS.
